UNITED STATES PATENT OFFICE

JAMES E. SPENCE, OF WHEELING, WEST VIRGINIA, ASSIGNOR TO HAZEL-ATLAS GLASS CO., OF WHEELING, WEST VIRGINIA, A CORPORATION OF WEST VIRGINIA

DESIGN FOR A CANDY JAR

Application filed December 15, 1930. Serial No. 38,004. Term of patent 7 years.

To all whom it may concern:

Be it known that I, JAMES E. SPENCE, a citizen of the United States, residing at Wheeling, in the county of Ohio and State of West Virginia, have invented a new, original, and ornamental Design for Candy Jar, of which the following is a specification, reference being had to the accompanying drawing, forming part thereof.

The figure is a perspective view of a candy jar, showing my new design.

I claim:

The ornamental design for a candy jar, as shown.

JAMES E. SPENCE.
